POWDER PUFF AND METHOD OF MAKING
THE SAME

Joseph E. Valentine, Plainfield, N. J., and Ralph J. Pena, New York, N. Y., assignors to Oxyzyn Company, a corporation of New Jersey

Application January 25, 1944, Serial No. 519,622

2 Claims. (Cl. 15—131.1)

This invention relates to powder puffs and the like and to the method of making the article.

An object of the invention is to provide a simple, practical and effective article of the kind described.

Another object of the invention is to provide a simple, practical and efficient method for making such an article.

Another object of the invention is to provide an improved manner of closing the opening through which the powder puff is filled with powder and the like.

Another object of the invention is to provide a powder puff with a suitable handle or grip.

Other objects will be in part obvious or in part pointed out hereinafter.

The invention accordingly consists in the features of construction, combinations of elements, arrangements of parts, and in the several steps and relation and order of each of said steps to one or more of the others thereof, all as will be pointed out in the following description, and the scope of the application of which will be indicated in the following claims.

The invention will best be understood if the following description is read in connection with the accompanying drawing, in which,

Figure 1 is a perspective view of the parts forming the puff closure shown in the relative arrangement in which they are sewed;

Figure 2 is a view of the article after the completion of the operation by which the parts are assembled together by sewing, and shows the puff inside out;

Figure 3 is a vertical section taken on the line 3—3 of Figure 2;

Figure 4 is a perspective view of the article after it has been turned right side out showing by the dotted line indicating the free edge of said flap the position of the closure flap before it has been reversed, and showing, by the full line indicating the free edge of said flap, the closure flap in extended position in the process of being reversed and brought around its line of stitching to overlie the opposite face of the puff;

Figure 5 is a perspective view of the completed article;

Figure 6 is a vertical sectional view similar to Figure 7 but without any filling or padding member;

Figure 7 is a vertical sectional view taken on the line 7—7 of Figure 5 and showing a filling or padding member contained within the puff closure; and

Figure 8 is a vertical sectional view similar to

Figure 3 but showing a filling member interposed and secured between the facing and supplementary backing members.

The powder puff disclosed herein, disregarding for the moment any filling or padding material which may, if desired, be used in the puff, comprises a facing member 11 (referred to in some of the claims as the main, front, or first, face or facing member) which is shown as fully circular, 10 a backing member 12 (referred to in some of the claims as the second or rear face or facing member) which is substantially circular but the periphery of which is flattened into a substantially straight, chord-like edge C, along a relatively small portion of its periphery, and what we may term a closure flap 13 (referred to in some of the claims as the supplementary rear face or facing), which is segmental in character and has an edge portion 14 substantially corresponding in curvature to the curvature of the periphery of the facing member 11 so that when said flap member 13 is superimposed on facing 11 its edge portion 14 will be substantially in vertical alignment with the edge of facing 11.

15 The members 11 and 12 may be of any desired material, velour or other pile fabric usually being preferred for a powder puff, and the flap member 13 may similarly be made of any desired suitable material, silk or rayon being preferred for 20 a powder puff, the face of said member 13 which in the final product becomes its under face being treated with a suitable adhesive, preferably one which is thermoplastic and so will not have an adhesive character until it is exposed to heat as by 25 being pressed by a heated iron when it is in position for forming the final product.

The parts 11, 12 and 13 are initially assembled to form an assembly which is inside out, with the outer surface of facing member 12 resting against 30 the outer surface of facing member 11, and with the flap member 13 interposed between members 11 and 12, and with its edge portion 14 vertically aligned with the edge of the portion of facing member 11 which is not covered by backing member 12, and extending under the chord-like edge portion C of member 12. With the parts in this position a circular row of stitching 15 is performed 35 extending completely around facing member 11 adjacent its periphery, and it will be seen that by this one operation facing member 11 and backing 40 12 are secured together around their peripheries from b to b as illustrated in Figure 2, but not along the edge C of backing member 12, and that facing member 11 and the closing flap member 13 45 have been secured along the edge portion 14 of

member 13 by the portion of stitching 15 extending from *a* to *a* as shown in Figure 2.

The assembly thus formed inside out is now turned right side out through the opening 16 between the edge C of member 12 and the portion of member 11 on which flap member 13 is superimposed during the step of forming the stitching 15.

After the members 11 and 12 are turned right side out the closing flap member 13 will extend down over the outer face of facing member 11 with its under or thermo-setting surface exposed. The next step is to reverse closing flap member 13 by bringing it around the edge of the member 11 and around portion *a*—*a* of the line of stitching 15 until closing flap 13 extends over the chord-like edge C of backing member 12 and is superimposed on backing member 12, thereby covering the portion of the inner surface of facing member 11 left uncovered by backing member 12. At the beginning of this step the closing flap 13 will be positioned as shown by the dotted line in Figure 4 and it will be moved through its extended position shown by the full line in Figure 4, to the final position shown in Figure 5, which illustrates the final product as it will appear after the closing flap 13 has been completely reversed over and around portion *a*—*a* of the stitching joining it to facing member 11, and after it has been pressed, as by a heated iron, to effect union between the adhesive on its under surface with the portion of the outer surface of backing member 12 which it overlies, thereby closing the opening 16 and forming a complete closure.

Before the opening 16 is closed by means of flap 13 powder may be inserted into the closure through opening 16, and if desired a filler or padding member 17 (Figure 7) which may suitably be made of cotton batting or the like may also be inserted through opening 16 at this time. The padding member, if employed, may preferably be added to the combination when the facing, backing, and closure flap or supplementary backing, are assembled, as by being placed under the back of facing member 11 and, desirably joined thereto, preferably at least by the portion of the stitching *a*—*a*, joining the segmental supplementary backing 13 to the facing, but on the side of facing 11 opposite to backing 13 as shown in Figure 8, whereby, when the assembly is turned right side out, positioning of the padding 17, so that it extends fully under the supplementary backing 13 and up to the edge of the completed puff under the supplementary backing, is ensured, thus giving desired thickness to the puff under the segmental backing.

By the method disclosed herein a simplified and highly practical means is provided for overcoming the difficulty long experienced in the art, of closing the opening between unstitched together edge portions of the facing and backing members through which the puff is turned right side out. After the puff has been turned right side out and filled with powder it has been found impractical if not impossible to close the said opening by machine stitching, and even hand stitching presented a difficult and time consuming operation, and one which was exceedingly difficult to perform without an obviously different appearance between this portion of the stitching and the portion obviously performed by machine. In accordance with our method the opening is sealed rapidly, effectively and neatly by the ther-

mo-setting of the adhesive surface of flap member 13, and at the same time the finished product is provided with a desirable handle portion, on which, if desired, a trade-mark or any other desired indicia may be printed or otherwise impressed.

It will thus be seen that there has been provided by this invention a method and an article in which the various objects hereinabove set forth together with many thoroughly practical advantages are successfully achieved. As various possible embodiments might be made of the features of the above invention and as the art herein described might be varied in various parts, all without departing from the scope of the invention, it is to be understood that all matter hereinbefore set forth or shown in the accompanying drawings is to be interpreted as illustrative and not in a limiting sense.

20. What we claim is:

1. As an article of manufacture a powder puff comprising a first, circular face member, a second face member corresponding substantially in size and shape to the first face member except that it has a segment cut away along a chord-like line defining one edge of the segment, and a third member having a curved edge corresponding to the curvature of the edge of the first face member, and of a size greater than the segment cut off said second face member, said first face member having stitching around its entire periphery by which said first base member is secured to said second face member, except along the said chord-like line of said second face member, and by which said first face member is secured to said third member along the edge of the portion of said first face member which is not covered by said second face member, said third member having its unstitched end extending over the unsecured edge of said second face member and being adhesively secured to said second face member.

2. The method of making a powder puff and the like which comprises superimposing on a facing member a backing member, with their face surfaces in contact and with said backing member covering at least a substantial portion of said facing member and having its edge aligned with the edge of said facing member throughout a substantial portion of its perimeter, and a supplementary backing member having a thermo-setting adhesive on one surface interposed between said facing and backing members with its non-adhesive surface opposed to the face surface of said facing member, said supplementary backing member being secured to said facing member along the portion of the perimeter of said facing member which is not secured to said backing member, thus forming a partially closed puff which is inside out, turning the puff right side out through the opening left between said facing member and the unsecured edges of said backing members, and drawing the supplementary backing member over the unsecured edge of said backing, so that a portion of its adhesive surface will overlie a portion of the front face of said backing member, and heat treating the article to adhesively secure together said backing and said supplementary backing members.
